(57) **CLAIM**

The ornamental design for a cell phone mount, as shown.

DESCRIPTION

FIG. 1 is a front perspective view of the cell phone mount showing our new design;
FIG. 2 is a right side view thereof;
FIG. 3 is a left side view thereof;
FIG. 4 is a top view thereof;
FIG. 5 is a bottom view thereof;
FIG. 6 is a front view thereof; and,
FIG. 7 is a back view of thereof.
The broken lines in the drawings depict parts of the cell phone mount that form no part of the claimed design.
